FRANK J. CURRAN AND WILLIAM McCLELLAN, OF NEW YORK, N. Y., ASSIGNEES, BY
MESNE ASSIGNMENTS, TO STEAM POWER, INC., A CORPORATION OF DELAWARE

STEAM BOILER

Application filed October 5, 1927, Serial No. 224,040. Renewed June 14, 1932.

The present invention relates to steam boilers of the semi-flash type and more particularly to a steam boiler construction in which steam may be generated and superheated substantially immediately in accordance with the power demand, whereby the steam temperature remains substantially uniform during operation of the boiler. The invention is particularly applicable to steam generation as motive power for automobiles, although it may be used for numerous other purposes as will be apparent to those skilled in the art.

With the forms of flash and semi-flash boilers heretofore employed in connection with automobiles, a considerable amount of time is generally consumed in starting before the engine develops full power, particularly after the vehicle has remained stationary for some time, and the time which elapses before the pressure drop in the steam line becomes sufficient to cause automatic operation of the main burner is considerable; consequently the time required for building up normal operating pressures is excessive, resulting in a comparatively slow "pick-up" or low acceleration when starting.

While the ordinary steamers or steam-operated automobiles have the disadvantages above pointed out, the form of boiler which we have devised overcomes the above disadvantages, when applied to automobile propulsion, and permits operation of automobiles equipped therewith with greater facility and with a faster "pick-up" or acceleration than that of steam automobiles heretofore employed.

In the apparatus which we have devised, an auxiliary superheater is employed together with separate heating means therefore, whereby the necessary heat may be imparted to the steam, in starting, to produce superheated steam and to develop the requisite power to attain rapid acceleration in starting, and to supply heat to the steam during normal operation, thereby reducing the amount of heat which is to be supplied by the main burner. By producing superheated steam at the time the engine is started the power is developed at the time when

it is most required, which is before the main burner has been put automatically into operation by the drop in steam pressure in the system, and furthermore, by the use of superheated steam the amount of condensation which takes place in the cylinders of the engine when starting is also greatly reduced. A substantially constant temperature of the steam may thus be obtained, during the operation of the boiler, and the loss of power in starting due to the temperature drop in the steam which ordinarily occurs during the time that elapses before constant operating conditions are obtained, is avoided. Furthermore, the troublesome fine adjustment required for the operation of the burner in order to have it come on automatically is obviated, and the efficiency of the operation of the boiler is greatly increased.

One of the objects of the present invention is to provide a steam boiler in which steam may be generated at substantially full load power on starting, so as to pick up the full load substantially immediately when required.

Another object of the invention is to provide a steam boiler which is particularly adapted for automobiles or other vehicles and in which the steam vaporizing coils and superheater coil or coils may be heated independently of a separate auxiliary superheating coil so as to develop full load capacity or power of the engine and whereby the separate auxiliary superheating coil may serve to supply the required heat to the steam when the engine is first put into operation or when starting the automobile. After the boiler is operating normally, the main burner may be automatically turned on and off in accordance with power requirements.

A further object of the invention is to provide means for keeping the auxiliary superheater in the boiler construction at a substantially constant temperature so as to prevent the usual temperature drop in the steam line such as ordinarily takes place when starting, whereby the usual pressure drop with the consequent loss of power is obviated.

Another object of the invention is to provide a steam boiler having greater economy.

of operation than that of boilers heretofore employed, and in which space in the boiler arrangement is economized so as to obtain a most compact construction occupying a minimum of space.

With these and other objects in view, the invention comprises the various features hereinafter described, and defined in the claims. The various features of the invention are illustrated in the accompanying drawings, showing the invention in its preferred form, in which

Fig. 1 is a view in elevation partly in section of the improved form of boiler;

Fig. 2 is a detail sectional view of the lower portion of the boiler showing the auxiliary superheater and auxiliary burner;

Fig. 3 is a horizontal sectional view taken on the line 3—3 of Fig. 1;

Fig. 4 is a sectional view taken on the line 4—4 of Fig. 1; and

Fig. 5 is a detailed sectional view of a valve for controlling the operation of the main burner in accordance with steam pressure.

Referring in detail to the drawings, our improved boiler comprises an outer casing or housing 10 within which is a preheating coil 12 extending downwardly in proximity to the inner surface of the housing, by means of which water, which is fed to the coil through a pipe 14 having a valve 16 therein, may be preheated or heated to any desired degree, the water being preferably heated to substantially its boiling point. From the coil 12 the water, or water and combined steam, passes through a connecting pipe 18 to a water drum 20.

The water drum preferably comprises two annular pipes 22 and 24 connected by one or more tubes 26 through which communication is established between the annular pipes. The feed water from the preheater coil 12 is preferably conducted to the lower pipe 24 of the water drum in which it becomes further heated, the water drum being heated by means of combustion gases passing through a grate 28 from a burner, as will be herein-after described. Connected preferably to the upper pipe 22 of the water drum are a series of pipes 30, each of which is connected to a steam generating coil similar to coil 32, through which water or water and steam passes from the water drum to a steam drum 34. The coils 32 are heated by combustion gases passing through the grate 28 and are preferably spiral in form, the convolutions of larger diameter being nearer the drum 34.

The steam drum 34 at the upper part of the boiler comprises a steam chamber having a series of tubes or flues 36 therein through which combustion gases pass to the upper portion or dome of the furnace. In order to attain flexibility in construction, the individual pipes 30 having the coils 32 therein, are positioned so as to pass upwardly through the

flues 36 and downwardly through the top of the drum 34, the ends of the pipes being so disposed as to discharge the contents tangentially into the steam drum, preferably at a downward angle of about 20° with the horizontal whereby the suspended or entrained particles of water will be thrown to the sides of the drum by centrifugal force and the disengaged steam will pass to the center of the drum, from which it is withdrawn through the perforated pipe 42. After entering the pipe 42, the steam passes to a superheating coil 44 directly below the steam drum 34 and from thence through a pipe 46, which passes out through the casing 10 to a control valve 48 which may be operated by suitable means such as a handle 50. From the control valve the steam passes through a pipe 52 to a main superheater coil 54 which, as above stated, is heated by means of combustion gases passing through the grate 28. The superheater coil 54 is connected to a pipe 56 which preferably passes outside of the housing 10 and is connected to an auxiliary superheater coil 60 positioned within a chamber 106 at the bottom of the boiler, the coil 60 being independently heated by means of a burner 62. In the portion of the pipe 56 outside of the boiler is a valve 58 by means of which the passage of steam from the superheater coil 54 to the auxiliary superheater coil 60 may be controlled. The chamber 106 in which the auxiliary superheater coil is located is preferably lined with heat insulating material or may be formed by packing suitable insulating material between the wall 10 and the burner walls or casing 80 leaving the desired space or chamber 106 for the coil. From the auxiliary superheater coil 60 the steam passes through a pipe 64 to the engine which is to be operated.

The gases of combustion from the burner 62 pass from the chamber 106 into the flue 70, which communicates with the flue 40, through which gases from the top or dome of the boiler are withdrawn, the combined gases passing through a pipe or conduit 72 to a chimney or other suitable exhaust. Connected to the steam drum 34 are a series of pipes or down-comers 66 through which the water which is discharged from or separated from the steam in the steam drum 34 passes to the water drum 20 preferably to the lower annular pipe 24 thereof. In the end of the pipe 66 is a check valve 68 adapted to permit passage of water downwardly through the pipe 66 into the water drum but serves to prevent passage of water or steam in the opposite direction. These down-comers are preferably located between the preheating coil 12 and the wall 10 of the furnace or boiler or may be located in vertical indentations in the coil 12 so as to be suitably protected from the hottest combustion gases.

In order to independently regulate the

heating of the main superheater coil 54 and the auxiliary coil 60, separate heating means are employed, one burner 74 being located just below the grate 28 preferably between a casing or partition 76 and the grate, the second burner 62 being located so as to heat coil 60 at the lower end of the boiler casing. The casing 76 may be of cast iron or other suitable material.

10 The burner 62 may be of any suitable form, but preferably comprises a cylindrical casing 80 in which are a number of orifices or burner nozzles 82, through which the fuel mixture passes, the mixture being burned in the chamber 106 in which the flames and hot gases of combustion come into contact with the auxiliary superheater coil 60, thereby superheating the steam to a degree depending upon the rate of passage of steam through the coil and the set of the burner control valve.

15 In order to supply the burners, a suitable fuel or fuel air mixture is conducted from a source of supply through a pipe 84 to pipes 86 and 88, having valves 90 and 92 respectively therein, by which the passage of the fuel mixture to the burners may be controlled as will be hereinafter more fully described. The fuel or mixture passing to the main burner 74 passes through the pipe 86, having preferably a single heating loop 94 therein, which is substantially horizontally disposed in the chamber 95 between the grate 28 and the coil 54 (see Figs. 2 and 3), and then enters the vaporizer 96, positioned above the pilot 98 (to be hereinafter referred to) and passes downwardly through the pipe 100 (see Fig. 1) to the atomizer nozzle 102 (see Figs. 2 and 3) at which the fuel or mixture is burned. The combustion gases produced pass through 20 the grate 28 into contact with the fuel vaporizer coil 94, and from thence into contact with the superheater coil 54, the water drum 20, the pipes 30 and coils 32 in the interior portion of the boiler, and serve to heat the preheater coil 12 to a greater or less extent, the gases coming finally into contact with the coil 44 before passing through the flues 36 of the steam dome 34. After passing through the flues 36, the gases pass through 25 the opening 38 into the flue 40 and from there through the pipe or conduit 72 from which the gases may be exhausted into the atmosphere or may be lead to a chimney or otherwise disposed of.

30 The fuel or fuel air mixture employed for heating the auxiliary superheater coil passes through pipe 88 controlled by the valve 92 (see Fig. 1) and passes through a coil or U 104 in the chamber 106, into a vaporizer or enlarged portion 108 and from thence into a pipe 110 connected to the nozzle 112, from which the fuel mixture issues and passes through a connection or passageway 114 into the chamber 115 within the burner casing 80.

35 From the chamber 115 the mixture passes

through the orifices 82 and is burned in the chamber or passageway 106 in which the auxiliary superheater coil 60 is located, thus heating the coil. The gases of combustion pass from the chamber or passageway 106 into the pipe or conduit 70, as above described and into a chimney, or are suitably exhausted to the atmosphere.

40 In the central portion of the grate, or conveniently positioned below the vaporizer 96 is a pilot 98 which is preferably supplied with fuel or a combustible mixture through a separate pipe 116 (see Fig. 1) and which remains continuously lighted during the operation of the boiler. The pilot serves to light the gases from the auxiliary superheater burner 62 when the burner is turned on, through the passageway 99 communicating between the chamber 106 and the space immediately above the pilot. The pilot preferably serves to also light the fuel mixture issuing from the nozzle 102 below the grate 28 when the main burner 74 is turned on, whereby when the steam supply has been cut off and the main burner has been extinguished, the pilot will 45 ignite the gas or fuel mixture when the steam control valve is again turned on. The pilot light serves, therefore, as above stated to light the auxiliary superheater burner 62 at the time the boiler is started or put into operation, and when a sudden steam demand is made on the boiler, the pilot serves also to light the main burner, which is preferably automatically operated, depending for its 50 operation upon the steam pressure in the boiler. In order to turn the main burner on and off in accordance with steam demand, a valve 90 is preferably employed, which is connected in the steam line, as for example by means of a pipe 87 which is connected to the pipe 56 so that when the pressure in the line falls below a predetermined amount the reduction in pressure causes the diaphragm 91 to move, and the valve head 93 to be lifted by the spring 89 from its seat, thus permitting 55 passage of fuel mixture through the pipe 86 whereby the main burner 74 is lighted. When the steam pressure is developed and exceeds a predetermined amount, the pressure causes the diaphragm 91 to be depressed against the 60 pressure or force of the spring 89 causing the valve head 93 to close, thus cutting off the supply of fuel mixture to the burner 74.

65 When the boiler is in operation and when the valve 92 controlling admission of fuel to the auxiliary superheater coil burner has been turned on, then when the throttle or handle 50 is operated to turn on full steam the valve 90 will be in the open position so that fuel will pass to the main burner, and the 70 boiler will be operated to generate maximum heat. After the pressure in the steam line has been built up to a predetermined amount, the valve 90 will operate as above explained to cut off fuel supply to the main burner 75.

which will then be extinguished. In the preferred form of the device which has been illustrated, the auxiliary superheater coil burner is preferably manually operated and the main burner is preferably automatically operated in the manner above described.

It is to be understood that the mode of controlling the operation or ignition of the main burner 102 may be varied or modified as will be apparent to those skilled in the art. The burners instead of being operated independently might be operated inter-dependently, either by manual regulation or through automatic regulation. We may, if desired, have the control valve 48 operatively connected to both the main burner control valve 90 and the auxiliary superheating burner control valve 92 so that when the handle 50 is turned so as to pass steam to the engine, both of the burner control valves will be turned on, thereby immediately supplying superheated steam at maximum capacity. An automatic reducing or cut-off arrangement, preferably thermostatically operated, might be employed for reducing or cutting off the supply of fuel to the auxiliary burner 62 so that when a predetermined maximum temperature limit, such as 800° F. for example, is reached, the heat supply to the steam will be reduced or cut off entirely. This thermostatic control may involve the use of a suitable thermostat 120 in the pipe 56 adjacent the point where it enters the casing on its way to the coil of the auxiliary superheater, a thermostatic valve 121 in the fuel line 88 in addition to the hand valve 92, and a suitable connection 122 between the thermostat 120 and the valve 121.

It is to be understood also, that instead of passing the combustion gases produced from the auxiliary superheater burner directly to the flue 72 to the chimney, it may be passed into the upper portion of the boiler, or through substantially the full length of the boiler so as to pass out through the passageway 38 with the gases from the main burner 102. We prefer, however, to employ the construction shown in the drawings in which the heat of the combustion gases is conserved by preheating the water passing to the coil 12 in a preheater coil 11 which serves to abstract a portion of the heat of the combustion gases from the burner 62.

While the invention has been described in its preferred form, it will be apparent that various changes or modifications may be made in the details of construction without departing from the spirit or scope of the invention as defined in the claims.

Having thus described our invention, what we claim is:

1. In a steam boiler of the semiflash type, a main heating fluid container; means for heating said fluid container; means for auto-

matically operating said heating means to supply the desired amount of heat within minimum and maximum predetermined limits; an auxiliary heating fluid container; and means independent of the heating means for said main heating fluid container for heating the said auxiliary heating fluid container. 70

2. In a steam boiler of the semiflash type, a main heating fluid container; means for heating the said main fluid container; means for automatically operating the said heating means within predetermined maximum and minimum steam pressure limits; an auxiliary heating fluid container; means for heating the said auxiliary heating fluid container, said heating means being operative to maintain the temperature of steam which is generated at substantially constant temperature. 75

3. In a steam boiler of the semi-flash type, a preheating coil; a water drum; a steam drum for the separation of steam and water; a series of steam generating coils connecting the said steam drum with the said water drum; a main superheater coil; a steam pipe leading from the said steam drum to the said main superheating coil; a control valve in said pipe for controlling admission of steam to an engine; an auxiliary superheater coil; a pipe connecting said main superheater coil with said auxiliary superheater coil; a main burner for heating the said main superheater coil; means for automatically regulating the said main burner dependent upon steam pressure; and a separately regulatable burner for heating the said auxiliary superheater coil. 90

4. In a steam boiler of the semi-flash type, a main heating fluid container; a heating means for said fluid container automatically operable with a predetermined drop in steam pressure when steam is drawn from the boiler; an auxiliary heating fluid container; heating means for said auxiliary fluid container; means for feeding water to the main heating fluid container; means for passing the steam generated through the said auxiliary fluid container; means for drawing off steam from the said auxiliary fluid container; and means for regulating the heating means for the auxiliary heating fluid container to maintain a substantially constant temperature. 105

5. In a steam boiler of the semiflash type, the combination of a water drum, a steam disengaging drum, a plurality of tubes inter-connecting the water drum and steam drum; a superheater; means for passing steam from said steam drum to the superheater; heating means for said tubes, steam drum and superheater; an auxiliary superheater connected to said superheater; means for independently heating said auxiliary superheater; throttle means for controlling the exit of steam from the boiler; and means for automatically controlling the first named heating means 110

125 130

in accordance with steam pressure so as to cause said heating means to operate after a predetermined drop in pressure in the steam line.

6. A boiler of the semi-flash type for generating steam comprising in combination heating coils for heating water and steam arranged in three stages, heating means for said heating coils, means controlling the application of heat to the coils of the last of said heating stages independently of the heating means for the other stages, and means for controlling the heating means for said other heating stages automatically to render

10 the heating means therefor effective or ineffective when the pressure of the steam is below or above a predetermined degree.

7. A steam boiler adapted for automobiles which comprises a preheating coil; means for feeding water to the said preheating coil; a water drum; a steam drum for the separation of steam and water; a main superheater coil; a steam line connecting the said steam drum with the said main superheating coil; a control valve in the said steam line for controlling supply of steam to an engine; an auxiliary superheater coil; a pipe connecting the said main superheater coil with the said auxiliary superheater coil; a main burner for heating the main superheater coil; a fuel supply pipe connected to said main burner; a valve in said fuel supply pipe for controlling passage of fuel therein; means operatively connecting the said valve to

35 a steam coil so as to operate the valve to supply fuel to the burner when the pressure exceeds a predetermined minimum and to close the valve when a predetermined maximum pressure is exceeded; an independently refulatable burner for heating the said auxiliary superheating coil; a pilot light for lighting the main burner; a passageway communicating between the pilot light and the said independently regulatable burner so as to light the last named burner when it is turned on.

8. In a steam boiler, a series of heating coils, heating means for the said heating coils automatically operable to supply heat in accordance with the steam demand within predetermined limits of steam pressure, a steam drum connected with said coils whereby the latter discharge water and steam into the drum, a grate in the boiler above the heating means for the said coils, a pilot for lighting the said heating means after it has been turned off, a superheater coil located in the boiler above the said grate, means for passing steam from the said drum to the said superheater coil, an auxiliary superheater coil located below the said grate, means for connecting the said superheater coil with the said auxiliary superheater coil, an independently controllable burner for heating the said auxiliary superheater coil, means for light-

ing the said burner by means of the said pilot, and means for controlling the passage of steam through the said auxiliary superheater coil.

9. In a steam boiler, a series of heating coils, means for passing water to the said heating coils, a steam drum connected to the said coils constructed and arranged to receive steam therefrom, a series of flue passages in the said drum, a burner to heat the said coils and the said steam drum, the products of combustion passing through the said flue passages, a pilot to ignite the fuel passing to the burner when the burner is turned on, a pipe for passing fuel mixture to the burner a portion of which is heated by the pilot whereby the fuel mixture is suitably vaporized, a valve for controlling admission of fuel to the said burner regulated by steam pressure and constructed and arranged to cut off passage of fuel when the steam pressure exceeds a predetermined amount, an auxiliary superheater coil connected to said superheater coil, a burner for independently heating the said auxiliary superheater coil, a pipe for passing fuel to the last-named burner, means for heating the said pipe to vaporize fuel therein, and means for controlling the operation of the last-named burner to maintain a substantially constant steam temperature of steam issuing from the said auxiliary superheater coil.

In testimony whereof, we affix our signatures.
